UNITED STATES PATENT OFFICE.

CHARLES F. SMITH, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A CASE FOR VACUUM-BOTTLES.

47,015.

Specification for Design.

Patented Feb. 23, 1915.

Application filed March 3, 1913. Serial No. 751,929. Term of patent 14 years.

To all whom it may concern:

Be it known that I, CHARLES F. SMITH, a citizen of the United States, and a resident of New Britain, in the county of Hartford, State of Connecticut, have invented a new, original, and ornamental Design for a Case for Vacuum-Bottles, of which the following is a specification, reference being had to the accompanying drawings, forming part hereof.

The drawing shows the structure in side elevation.

I claim:

The ornamental design for a case for vacuum bottles as shown.

CHARLES F. SMITH.

Witnesses:

F. G. RUSSELL,
A. G. ANDERSON.
